UNITED STATES PATENT OFFICE

CHARLES J. RICHTER, OF BURWYN, ILLINOIS, ASSIGNOR TO THE GOSS PRINTING PRESS CO., OF CHICAGO, ILLINOIS, A CORPORATION OF ILLINOIS

DELIVERY APPARATUS FOR PRINTING PRESSES

Application filed September 10, 1928. Serial No. 305,028.

My invention relates to delivery apparatus for printing presses of the type arranged for separating into unit piles the newspapers coming from a press as the completed papers 5 are taken from the folder and deposited one at a time by a rotary fly device or other suitable delivery mechanism upon a delivery belt or other receiver. It is the object of my invention to provide in an apparatus of this 10 type an improved form and arrangement of parts adapted to act upon the series of papers at predetermined intervals in the operation of the press for causing one of such papers to assume a changed position on the receiver as 15 compared with the position of the remaining papers thereon whereby the papers on the receiver are divided into unit bunches.

It is one of the objects of my invention to 20 provide improved means for moving a paper at timed intervals for causing it to take a changed position on the receiver for indicating the division of the papers into unit bunches on the receiver, and to provide improved means for better controlling the movement 25 of the paper. To this end, it is one of the objects of my invention to provide a construction of this type comprising means which are caused to grip the paper to be moved into changed position so as to hold the paper 30 firmly for the required movement and then preferably to hold the paper in position until one or more subsequently delivered papers are piled on top of it so as to insure its being retained in the changed position. It is an 35 other object of my invention to provide a construction and arrangement of this type in which the grippers are withdrawn from the gripped paper and from the pile of papers by movements respectively in opposite directions 40 whereby there shall be a minimum tendency to displace the papers by such withdrawal.

It is another object of my invention to improve apparatus of this type in sundry details hereinafter pointed out. The preferred means by which I have accomplished my several objects are illustrated in the drawings and are hereinafter specifically described.

50 That which I believe to be new and desire to

cover by this application is set forth in the claims.

In the drawings,—

Fig. 1 is a view of the preferred form of my improved delivery apparatus as seen from 55 one end of the press;

Fig. 2 is an end view of the apparatus shown in Fig. 1 as seen from the left in said Fig. 1;

Fig. 3 is a vertical section taken at the line 60 3—3 of Fig. 1, but showing a changed position of certain of the parts;

Fig. 4 is a view similar to Fig. 3 but showing another changed position of the parts;

Fig. 5 is a vertical cross section taken at 65 line 5—5 of Fig. 1;

Fig. 6 is a view similar to Fig. 5 but showing a changed position of the parts, being substantially a section taken at line 6—6 of Fig. 7; and 70

Fig. 7 is a view similar to a portion of Fig. 1 but showing a changed position of the parts.

Referring to the several figures of the drawings, in which corresponding parts are indicated by the same reference characters,— 75 15 indicates the frame of a printing press in connection with which my improved apparatus is used, the frame 15 being shown as provided with folding apparatus comprising a cylinder 16 and fold-laying rollers 17 of any 80 approved type. A shaft or bar 18 extending transversely of the printing press frame is provided with a plurality of guide bars 19 of the ordinary type along the faces of which the papers are delivered in regularly timed 85 succession from the folding apparatus. A plurality of rotary fly devices 20 are mounted upon a shaft 21 supported by the framework and driven in timed relation with respect to the downward movement of the papers so as to receive the papers successively in the pockets provided by the arms 22 of the rotary fly devices in the well understood manner for turning the papers out of the direct downward path along the curved portions 23 90 95 of the guide bars so as to deliver the papers in regularly piled arrangement upon a receiver. In the form shown and in the arrangement ordinarily employed, the receiver comprises a plurality of endless belts 24 100

which are supported by sheaves 25 which in turn are supported and driven by a shaft 26, the belts being omitted from Fig. 1 of the drawings for the sake of clearness of illustration. The means for driving the various parts in timed relation as is well understood in the art is not illustrated, since such means in and of itself forms no part of my present invention.

- 10 The division of the papers into unit piles upon the receiver comprising the belts 24 by a change in the position of a paper upon the receiver at timed intervals for indicating the limits of the unit piles is effected by means 15 of stops normally held out of the path of the papers and movable into the path of the papers at the desired intervals. In the construction illustrated, the stops are in the form of stop arms 27 which are mounted upon a 20 rock shaft 28, such stop arms 27 being mounted in such spaced relation as to engage the edge portions of a paper being delivered as is indicated in Fig. 1 which shows a paper 28^a in position a short distance above said arms 27. 25 The arms 27 are normally held in position out of the path of the papers moving along the faces of the guide bars 19, as is shown in Fig. 2. In the form of apparatus as illustrated in my drawings, the stop arms 27 are 30 swung downwardly a short distance into the path of the papers so as to engage one of said papers, the arms being then moved downwardly with the paper for depositing the paper upon the receiver comprising the 35 belts 24 in a different position upon the receiver from that in which the other papers are deposited thereon. After a number of papers have been delivered on top of the paper in changed position, the arms 27 are 40 moved longitudinally of the shaft 28 for carrying the arms out of engagement with the stopped paper and out of the path of the papers, such arms being moved in opposite directions away from each other so as to have 45 the minimum tendency to displace the position of adjacent papers upon the receiver. The stop arms 27 are then moved upwardly to raised position corresponding to that shown in Fig. 2, and are then given reverse horizontal movements along the shaft 28 for bringing 50 them again to normal position as shown in Figs. 1 and 2 ready for another operative movement.

The means for mounting the stop arms 27 55 in position and for giving them the desired movements as described comprise sleeves 29 and 30 which are slidably mounted upon the shaft 28, being held against swinging movement with respect to said shaft by suitable 60 keys 31. In the construction shown, the stop arms 27 are formed integrally with the sleeves 29 and 30, but they may be otherwise rigidly secured thereon as may be desired. The sleeves are normally held in the position 65 shown in Fig. 1 by means of coiled springs

32 bearing at their inner ends upon the ends of the sleeves and bearing at their outer ends against collars 33 rigidly mounted upon the shaft 28. The arrangement is such that when the sleeves 29 and 30 are moved outwardly along the shaft 28 away from each other, the stop arms 27 are moved horizontally in transverse direction out of the path of the papers being delivered along the faces of the guide bars 19.

The rocking movement of the shaft 28 for swinging the stop arms 27 vertically is effected by means of an arm 34 fixed upon the end of the shaft 28 provided at its outer end with a roller 35 revolvably mounted thereon in position to bear upon a cam 36 rigidly mounted upon the shaft 28. As is best shown in Fig. 2, the cam 36 is of circular formation except for a portion 37 thereof which is also of circular formation but upon a smaller radius, an intermediate step between the outer circumference and the portion 37 being provided at 38. At its opposite end, the portion 37 is connected with the outer circumference by means of a rise 39. In the construction illustrated, the opposite edge portion of the cam is formed in the same manner, comprising portions 37, 38 and 39, a shield or guard 40 being provided for covering the portions 37, 38 and 39 when desired. In the position of the parts illustrated in Fig. 2, the shield 40, pivoted at 41 upon the cam 36, is held in position by means of a bolt 42 with its circular outer edge in concentric position with respect to the outer circumference of the cam 36. The arrangement is such that upon the removal of the bolt 42 the shield 40 can be moved about the pivot 41 into changed position so as to make the cam portions 37, 38 and 39 effective, the shield being held in such changed position by the bolt 42 replaced through the opening in the shield and through an opening 43 in the cam.

When the parts are in the position as shown in Fig. 2, with the roller 35 upon the periphery of the cam 36, and with the cam 36 rotating in counter-clockwise direction in Fig. 2, upon a slight additional movement of the cam 36 in counter-clockwise direction in said figure the roller 35 is brought into engagement with the intermediate step 38 of the cam, serving to permit the rock shaft 28 to rotate in counter-clockwise direction for swinging the stop arms 27 downwardly into the position as shown in Fig. 3. Upon continued rotation in the same direction, the roller 35 is brought into engagement with the portion 37 of the cam, serving to bring the stop arms 27 into still further lowered position adjacent to the delivery belts 24, as is shown in Fig. 4. As the cam 36 continues to rotate, the roller 35 is later brought into engagement with the rise 39, serving to raise the stop arms 27 again to the position as shown in Fig. 2. With the shield 40 in the

70

125

130

position illustrated in Fig. 2, the stop arms 27 will be given only one movement out of the normal position as shown in Fig. 2 for each rotation of the cam 36 and the shaft 26. As will be readily understood, when the 5 shield 40 is moved into changed position as above described so as to clear the edge of the cam, in such case the stop arms 27 are given two swinging movements into the position shown in Fig. 4 for each rotation of the cam 36 and the shaft 26.

The transverse horizontal movement of the stop arms 27 out of the path of the papers being delivered is effected in the construction shown by movement of the sleeves 29 and 30 15 outwardly in opposite directions along the shaft 28. For effecting this longitudinal movement of the sleeves 29 and 30, each of the sleeves is provided at its inner end with a conical head portion 44. For operating upon the sleeves 29 and 30 by pressure upon the 20 conical heads 44, I have provided a cam member 45 which is provided with a loop 46 at its lower end about the shaft 26, being bifurcated at its upper end for engagement at opposite sides of the shaft 28. The cam member 45 is actuated longitudinally of itself by means of a roller 47 revolvably mounted thereon engaging the face of a cam 48 rigidly 25 mounted upon the shaft 26. At its bifurcated upper end, the member 45 is provided with diagonally disposed cam portions 49 at opposite sides adapted by engagement with the conical portions 44 of the sleeves to move such sleeves outwardly against the action of the springs 32. Upon the retraction of the cam member 45 downwardly, the sleeve 29 and 30 will, of course, be moved inwardly toward each other along the shaft 28 by the 30 action of the springs 32.

As is best shown in Fig. 3, each of the stop arms 27 is provided at its forward end with a gripper 50 which is pivotally mounted thereon so as to be capable of swinging downwardly into gripping engagement with a 40 paper 51 as illustrated in Fig. 4. The means for actuating the gripper 50 comprise a rod or link 52 pivotally connected with the gripper 50 slidably mounted at its opposite end through an opening in a lug 53 carried by the sleeve 29 or 30. Springs 54 are mounted upon the rods or links 52 bearing at their rear ends against the lugs 53 and bearing at their forward ends against blocks 55 fixedly mounted upon the links 52, the arrangement being such that the springs 54 serve normally for holding the grippers 50 in their closed position.

Means is provided for operating the grippers 50 by engagement with the links 52. Such means comprises curved arms 56 fixedly mounted upon a shaft 57 below the shaft 28. One of the curved arms 56 (the one at the left in Fig. 1) is provided with a laterally 50 extending lug 58 which engages the face of

a cam 59 mounted upon the shaft 26. The curvature of the arm 56 is such that when the arm 56 is held in its uppermost position by engagement with the cam 59 as shown in Fig. 3, the upper end portion of such curved arm stands in concentric position about the axis of the shaft 28, with such curved portion in effective engagement with a pin 60 extending transversely from the block 55. The arrangement is such that under such conditions the link 52 is held moved toward the right in Fig. 3 against the action of the spring 54 for holding the jaw or gripper 50 in its opened position. Upon a very slight rotation of the cam 59 in counter-clockwise direction in Fig. 3 from the position there shown, the lug 58 passes out of engagement with the outermost periphery of the cam 59 serving to permit the curved arm 56 to move quickly toward the left into the position shown in Fig. 4 in which the gripper 50 is held by the spring 54 in its closed position.

In the construction shown, the shaft 26 is geared so as to have a single rotation for each fifty papers delivered downwardly from the folding apparatus so as to assure the stop arms 27 being given a downward stroke for each fiftieth paper delivered. Starting with the parts in the position as shown in Fig. 2, with the stop arms 27 held in raised position 50 out of the path of movement of the papers, with the cam 59 holding the curved arm 56 in position for maintaining the grippers 50 in opened condition, and with the cam member 45 in its lowered position so as to hold the stop arms 27 in their innermost positions as shown in Fig. 1,—upon a slight rotation of the shaft 26 in counter-clockwise direction the roller 35 is brought into engagement with the intermediate step 38 of the cam 36, serving to bring the stop arms 27 to the position shown in Fig. 3. With the arms 27 brought down in timed relation with respect to the movement of the papers, one of the papers is brought promptly into engagement with the gripper 50, and the gripper is almost immediately moved downwardly into operative engagement with the paper by reason of the changed position of the cam 59 due to rotation of the shaft 26. Almost immediately thereafter, upon the continued rotation of the shaft 26, the roller 35 passes into engagement with the portion 37 of the cam 36 serving to move the stop arms 27 with the paper gripped thereby into the position shown in Fig. 4 in which the paper is held a short distance above the delivery belts 24. The cam 59 is so arranged as to permit the gripper 50 to remain closed for some little time until a plurality of other papers have been delivered by the rotary fly devices on top of the gripped paper, such additional papers serving to weight the gripped paper down firmly in position so as to prevent any material disturbance of such gripped paper when the stop arms are being 100 105 110 115 120 125 130

moved out of engagement therewith. After a number of papers have been so piled upon the gripped paper, the curved arm 56 is moved toward the right in Fig. 4 by the cam 59 5 against the action of the spring 54 for opening the gripper 50. The parts are so arranged that shortly after the grippers 50 are opened, the cam member 45 is moved upwardly for causing the sidewise movement of the arms 10 27 out of the path of movement of the papers. Inasmuch as the stop arms 27 are moving in opposite directions away from each other, such movement has a very slight tendency to disarrange the papers upon the receiver. The 15 arrangement is such that shortly after the levers 27 have been moved to the limit of their transverse movement, the roller 35 comes into engagement with the rise 39 of the cam 36 serving to raise the stop arms 27 to the 20 position as shown in Fig. 2. Shortly thereafter, the cam 48 has reached such a position as to permit the stop arms to move inwardly again to their normal position as shown in Fig. 2.

25 The arrangement as illustrated and as above described is such that the entire cycle of operations by which the stop arms are moved downwardly, then sidewise, then upwardly, and then again sidewise in the reverse 30 direction, takes place during about three-eighths of a rotation of the shaft 26, wherefore it will be understood that the mechanism is in position for a second operation well in 35 advance in case it is desired to give the mechanism two operations for each rotation of the shaft 26.

By the use of my improved apparatus, the paper is displaced from its normal position on the receiver so as to divide the papers into 40 piles of either twenty-five or fifty papers each depending on whether or not the shield 40 is being employed. It will, of course, be understood that the rotation of the shaft 26 can be regulated for obtaining unit piles of a different size if desired. By reason of the movement of the stop arms in opposite directions out of engagement with the stopped paper and the other papers adjacent thereto on the receiver, this withdrawal of the stop arms is 45 effected with very little tendency to disturb the relative positions of the papers, so that the displaced paper serves effectively for indicating the divisions between the several piles or bunches of papers. By reason of the use 50 of the grippers in connection with the stop arms, the movement of the critical papers into changed position on the receiver is made more certain inasmuch as the paper is under 55 positive control during the change of position and for a limited time thereafter until a later delivered paper or papers have been piled on top so as to serve by their weight to prevent subsequent movement of the paper 60 with respect to the adjacent papers.

While I prefer to employ the form of mechanism as shown in my drawings and as above described, it is to be understood that my invention is not to be limited to such form except so far as the claims may be so limited 70 by the prior art, since it is evident that changes might readily be made with respect to the forms of mechanism employed without departing from the spirit of my invention. 75

I claim:—

1. In a delivery apparatus for papers moving downwardly in timed relation, the combination of a receiver, means serving normally to deposit the papers in regularly piled arrangement on said receiver, and means adapted at intervals to grip one of said papers and to carry the paper downwardly into changed position on said receiver as compared with the position at which the other papers are deposited on said receiver. 80

2. In a delivery apparatus for papers moving downwardly in timed relation, the combination of a receiver, means serving normally to deposit the papers in regularly piled arrangement on said receiver, gripping means normally held out of the path of said papers and movable into said path, and means for controlling and actuating said gripping means, adapted at time intervals to cause said gripping means to move into gripping engagement with one of said papers, then to move downwardly with said paper for depositing the paper in changed position upon said receiver as compared with the position at which the other papers are deposited thereon, and then to release the paper and to withdraw from engagement therewith by a movement substantially parallel with the 105 plane of the paper. 90

3. In a delivery apparatus for papers moving downwardly in timed relation, the combination of a receiver, means serving normally to deposit the papers in regularly piled arrangement on said receiver, a gripper, means adapted normally to hold said gripper out of the path of said papers and adapted at timed intervals to cause said gripper to move into position to engage the forward 110 edge of one of said papers and to grip the same and then to move downwardly with the paper for depositing the paper upon said receiver in changed position thereon as compared with the position taken by the other 120 papers, and means for releasing the gripper from the paper and withdrawing the gripper by a transverse movement along the face of the receiver underneath the subsequently deposited papers. 115

4. In a delivery apparatus for papers moving downwardly in timed relation, the combination of a receiver, means serving normally to deposit the papers in regularly piled arrangement on said receiver, stops normally 125

held out of the path of said papers and movable into said path, and means for controlling the position of said stops adapted at timed intervals to cause the stops to move into position to engage one of said papers, then to move downwardly with said paper for depositing the paper in changed position on said receiver as compared with the position at which the other papers are deposited thereon, and then to move simultaneously in opposite directions out of engagement with said paper.

5. In a delivery apparatus for papers moving downwardly in timed relation, the combination of a receiver, means serving normally to deposit the papers in regularly piled arrangement on said receiver, two stop arms swingably mounted above said receiver at opposite sides of the path of movement of the papers, means for controlling the angular position of said stop arms for holding them normally out of the path of said papers, for causing them at timed intervals to move downwardly together into position to engage and stop one of said papers, and then to move downwardly with the paper for depositing it in changed position on said receiver as compared with the position at which the other papers are deposited thereon, and means for moving said stop arms simultaneously in opposite directions transversely of the papers out of engagement therewith.

6. In a delivery apparatus for papers moving downwardly in timed relation, the combination of a receiver, means serving normally to deposit the papers in regularly piled arrangement on said receiver, a rock shaft extending above said receiver, two stop arms slidably mounted on said rock shaft at opposite sides of the path of movement of the papers and adapted to swing about the shaft but held against swinging movement with respect thereto, gripping means carried by said stop arms for holding a paper securely in position on said arms, means for controlling the angular position of said rock shaft for holding the stop arms normally out of the path of said papers and for causing said stop arms and grippers at timed intervals to move downwardly into position to engage and grip one of said papers and then to move downwardly with the paper for depositing the paper in changed position on said receiver as compared with the position at which the other papers are deposited thereon, means for operating said grippers in timed relation, and means for withdrawing the arms and grippers from engagement with the paper by movements of said arms in opposite directions along said shaft.

7. In a delivery apparatus for papers moving downwardly in timed relation, the combination of a receiver, means serving normally to deposit the papers in regularly piled

arrangement on said receiver, a rock shaft extending across above said receiver, two sleeves slidably mounted on said rock shaft but held against rotary movement with respect thereto, stop arms carried by said sleeves and movable angularly therewith as said shaft is rocked, gripping means carried by said arms for holding a paper securely in position thereon, means for controlling the angular position of said rock shaft for holding said arms normally out of the path of said papers and for causing such stop arms and grippers at timed intervals to move downwardly into position to engage and grip one of said papers and then to move downwardly with the paper for depositing the paper in changed position on said receiver as compared with the position at which the other papers are deposited on said receiver, means for operating the grippers in timed relation for gripping and releasing the paper, and means for moving said sleeves longitudinally of said shaft for carrying the arms and grippers out of engagement with the paper.

8. In a delivery apparatus for papers moving downwardly in timed relation the combination of a receiver, means serving normally to deposit the papers in regularly piled arrangement on said receiver, a rock shaft extending across above said receiver, two sleeves slidably mounted on said rock shaft but held against rotary movement with respect thereto, stop arms carried by said sleeves and movable angularly therewith as said shaft is rocked, gripping means carried by said arms for holding a paper securely in position thereon, means for controlling the angular position of said rock shaft for holding said arms normally out of the path of said papers and for causing such stop arms and grippers at timed intervals to move downwardly into position to engage and grip one of said papers and then to move downwardly with the paper for depositing the paper in changed position on said receiver as compared with the position at which the other papers are deposited on said receiver, means for operating the grippers in timed relation for gripping and releasing the paper, and a cam adapted by a movement into position between said sleeves to move the sleeves longitudinally of the shaft for carrying the arms and grippers out of engagement with the paper.

9. In a delivery apparatus for papers moving downwardly in timed relation, the combination of a receiver, means serving normally to deposit the papers in regularly piled arrangement on said receiver, two stop arms swingable vertically above said receiver into and out of the path of said papers and also movable horizontally into and out of the path of said papers, and means for giving said stop arms a succession of movements in timed relation to the movement of the papers, serving

70

75

80

85

90

95

100

105

110

115

120

125

130

to move the stop arms downwardly into the path of the papers, thereafter to move said stop arms horizontally away from each other out of the path of the papers, thereafter to raise said stop arms, and then to move said stop arms toward each other ready for another operative downward stroke.

10. In a delivery apparatus for papers moving downwardly in timed relation, the combination of a receiver, means serving normally to deposit the papers in regularly piled arrangement on said receiver, two stop arms swingable vertically above said receiver into and out of the path of said papers and also movable horizontally into and out of the path of said papers, and means for giving said stop arms a succession of movements in timed relation to the movement of the papers, serving to move said stop arms downwardly into the path of the papers for engaging one of said papers, then to move such stop arms downwardly with said paper, thereafter to move the stop arms horizontally away from each other out of the path of the papers, thereafter to raise said stop arms, and then to move the stop arms toward each other ready for another operative downward stroke.

11. In a delivery apparatus for papers moving downwardly in timed relation, the combination of a stop arm swingingly mounted on a horizontal axis, a gripper pivotally mounted on said stop arm, operating means for opening and closing said gripper, yielding means for holding said gripper normally in closed position, and a curved arm serving by engagement with said gripper operating means to hold said gripper open against the action of said yielding means and having its operative portion in concentric form about the axis on which said stop arm is mounted whereby said gripper may be held open as the stop arm is given its vertical swinging movement.

12. In a delivery apparatus for papers moving downwardly in timed relation, the combination of a stop arm swingingly mounted on a horizontal axis, a gripper pivotally mounted on said stop arm, operating means for opening and closing said gripper, yielding means for holding said gripper normally in closed position, a curved arm serving by engagement with said gripper operating means to hold said gripper open against the action of said yielding means and having its operative portion in concentric form about the axis on which said stop arm is mounted whereby said gripper may be controlled independently of vertical swinging movement of the stop arm, and means for moving said curved arm into and out of position for holding said gripper open.

13. In a delivery apparatus for papers moving downwardly in timed relation, the combination of a receiver, means serving normally to deposit the papers in regularly piled

arrangement on said receiver, two stop arms swingingly mounted on a horizontal axis and movable toward and from said receiver into and out of the path of the papers and also movable transversely into and out of the path of the papers, grippers pivotally mounted on said stop arms, operating means for opening and closing said grippers, yielding means for holding said grippers normally in closed position, curved arms serving by engagement with said gripper operating means to hold said grippers open against the action of said yielding means and having their operative portions in concentric form about the axis on which said stop arms are so mounted whereby said grippers may be controlled independently of vertical swinging movement of said stop arms, and means for moving said curved arms and said stop arms in timed relation to the movement of the papers, serving to swing the stop arms downwardly into the path of the papers at timed intervals, then to close the grippers upon a paper stopped thereby, then to swing the stop arms downwardly with the grippers closed upon said paper, then to open said grippers for releasing the paper, then to move said stop arms transversely out of the path of the papers, then to raise said stop arms, and then to give the grippers reverse transverse movements into position for another cycle of operations.

14. In a delivery apparatus for papers moving downwardly in timed relation, the combination of a receiver to which said papers are delivered, means adapted at intervals to engage one of said papers and to cause said paper to take a different position on said receiver as compared with the remaining papers, and means for holding said paper against movement either forwardly or backwardly after its delivery to said receiver until at least one subsequently delivered paper has been piled on top.

15. In a delivery apparatus for papers moving downwardly in timed relation, the combination of a receiver to which said papers are delivered, swingingly mounted arms, means for controlling the position of said arms adapted to hold the arms normally in raised position above the path of the papers and adapted at intervals to permit said arms to swing downwardly into the path of the papers for causing one of said papers to take a different position on said receiver as compared with the remaining papers, and gripping means carried by said arms adapted to grip said one paper and to hold it against movement either forwardly or backwardly after its delivery to said receiver until at least one subsequently delivered paper has been piled on top.

CHARLES J. RICHTER.
